UNITED STATES PATENT OFFICE.

OSCAR P. ERHARDT, OF WEST HAVEN, CONNECTICUT, ASSIGNOR TO THE A. C. GILBERT COMPANY, OF NEW HAVEN, CONNECTICUT, A CORPORATION OF CONNECTICUT.

SEWING-MACHINE MOTOR.

Application filed December 21, 1917. Serial No. 208,249.

To all whom it may concern:

Be it known that I, OSCAR P. ERHARDT, a citizen of the United States, residing in the town of West Haven, county of New Haven, and State of Connecticut, have invented certain new and useful Improvements in Sewing-Machine Motors, of which the following is a full, clear, and exact description.

10 This invention relates to motors for driving sewing machines, and it has particular reference to a portable motor attachment which can be readily applied to and removed from sewing machines of various makes. When placed on the machine, my improved motor drives the hand wheel very effectively by friction. One of the primary objects of my invention is to provide a simple, convenient and serviceable motor attachment of the portable type, which can be used equally well with sewing machines of different patterns and different diameters of hand wheels.

Another object of the invention is to provide an electric motor drive in which a friction pulley or wheel on the motor shaft is held in the proper relation to the machine wheel.

Another object of my invention is to provide a motor attachment which can be very readily and conveniently applied to the head of the sewing machine and readily detached therefrom.

Another object of the invention is to furnish a very simple and convenient arrangement whereby the drive wheel on the motor shaft rests against the machine wheel by gravity and whereby the motor readily accommodates itself to machine wheels of different diameters.

Another object of the invention is to furnish a driving attachment for sewing machines which is of a convenient detachable type and can be mounted on the machine head when the attachment is in use, so that it will not take up space on the machine table and be in the way. The improved device has, in this latter respect, all of the advantages of certain attachments which have heretofore been built onto the sewing machine head as a permanent part of the machine; and, in addition, it has the advantage of ready removability from the machine, so that the motor member when

removed can be used for other purposes 55 such as operating a beverage mixer, fan, massage vibrator, etc. In accordance with my invention, the motor member can be readily detached as a unit, and it is of such a character that it can be readily used for 60 other purposes than the driving of sewing machines.

To these and other ends, the invention consists in the novel features and combinations of parts to be hereinafter described 65 and claimed.

In the accompanying drawings:

Fig. 1 is a fragmentary front elevation of a sewing machine head equipped with a motor attachment embodying my im- 70 provements;

Fig. 2 is a rear view of the parts shown in Fig. 1;

Fig. 3 is a top plan view;

Fig. 4 is an end view partly broken away; 75

Fig. 5 is a section on line 5—5 of Fig. 3, with the motor shown in dotted lines; Figs. 6, 7 and 8 are detail views;

Fig. 9 is a top plan view of a sewing machine equipped with an attachment of some- 80 what modified form;

Fig. 10 is a section on line 10—10 of Fig. 9; and

Figs. 11 and 12 are details of the attachment shown in Figs. 9 and 10. 85

In the drawings, I have shown my improved attachment applied to a sewing machine of well-known type having a head 20 only partially shown, and the usual machine wheel or hand wheel 21 fixed to a shaft 22, 90 which has a bearing in a sleeve-like projection 23 on the head. The sleeve-like bearing projection or boss is a feature of practically all sewing machines now on the market, and in the forms of my invention herein shown, 95 it is to this part of the machine that the attachment is applied. In the form shown in Figs. 1 to 8, the attachment consists primarily of a supporting frame 24, a cradle 25 pivoted thereto to swing in a vertical 100 plane, and a motor member 26 carried by the cradle and having a friction drive wheel or pulley 27 on the shaft 27^a thereof adapted to engage the periphery of the machine wheel. The frame 24 is applied to the boss 105 or bearing projection 23, for which purpose it is provided with a crescent-shaped portion 28 shaped to extend partially around said

boss and having two spaced points 29 to bear thereon. These bearing points 29 co-operate with a clamping screw 30 threaded through one extremity 31 of the crescent. 5 The axis of the screw is preferably about half way between the spaced bearing points 29, and the points 29 and the point 31^a of screw 30 will engage the bearing boss or projection at the apices of an isosceles triangle, 10 as shown in Fig. 5. The inner end 31^a of the screw is preferably formed with a sharp point, which is suitably hardened so that it will bite into the material of the machine frame when the screw is screwed inwardly 15 with a small wrench or the like, thereby clamping the frame 24 securely to the machine head alongside the hand wheel, in the space between the hand wheel and the main part of the machine head, the body of the 20 frame 24 being substantially parallel to the hand wheel, as shown in Fig. 1, and extending rearwardly therefrom in the example shown. The rearwardly extending portion of the frame consists of an extension 32 25 which is directed upwardly and rearwardly from the crescent-shaped portion 28 in the plane of the latter, and serves as a mounting for a guide rod 33, on which the cradle 25 is adjustably mounted for longitudinal 30 sliding movement. The rod 33, in the form shown, extends from that side of the frame 24 which is away from the hand wheel and lies slightly back of the machine head, as shown in Fig. 3. The cradle 25 is formed 35 of a flat metal arm having spaced perforated knuckles 34 at the upper end of the same, which fit over the guide rod 33, whereby the cradle is pivotally mounted on the guide rod, although it can be readily slid along the 40 same to allow for the alignment of the drive pulley with the machine wheel. The motor member is mounted on the lower end of the cradle, as hereinafter described. Between the spaced knuckles 34 at the upper end 45 of the cradle is a cam member 35, shown in detail in Fig. 8, having a perforation 36 fitting over the guide rod. The cam member has a cam projection 37 at the lower part thereof adapted to engage the edge 38 of 50 the cradle between the knuckles, and the cam is also provided with a manipulating handle or extension 39, which projects forwardly of the machine in the example shown at a point above the head, where it 55 is readily accessible. In the upper part of the cam member 35 is mounted a set screw 40 engaging a threaded opening in the cam member, which communicates with the perforation or bore 36, so that the inner end 60 of the set screw 40 may be engaged with the guide rod 33, as shown in Fig. 5.

When the parts are in the operative position, the cradle usually extends downwardly and rearwardly from the upper end of the 65 upward and rearward extension 32 of the

frame 24. After the cradle has been adjusted longitudinally, it may be clamped in position by the set screw 40, as will be obvious. The lower end of the cradle 25 is extended laterally, as shown at 41, and carries the motor member 26 on the upper surface thereof, the connection between the motor member and the extension 41 being a detachable one. The motor member selected for illustration is of the type illustrated 70 in the application of Alfred C. Gilbert, Serial No. 203,975, and is adapted for a multiplicity of different uses. It is provided at the lower part with spaced integral lugs 42, between which a block 43 75 is detachably clamped by screws 44, substantially as disclosed in said Gilbert application, the lower end of the block 43 being provided with a tapped hole as in said application. This tapped hole, which it is 80 not necessary to show herein, registers with a perforation 45 in the cradle extension 41, and the motor member is detachably held in place by a set screw 46 which passes upward through the opening 45 and engages the 85 threads in the block 43 attached to the casting of the motor member.

The operation of the improved attachment will be more or less obvious from the foregoing description. The frame member 20 is applied to the bearing boss 23 in the manner shown in Fig. 1, preferably with the arm 32 extending toward the rear of the machine, so that the motor attachment will be out of the way, the motor being located at the rear of the machine. The motor, which is detachably mounted on its cradle in the manner previously described, can be attached to the guide rod 33 of the supporting frame either before or after the member 24 has been applied to the head of the machine. When placed on the rod, the cradle may be adjusted longitudinally, so as to align the drive wheel on the motor shaft with the machine wheel. A considerable range of adjustment is provided for by the guide rod 33, so that the drive pulley on the motor shaft can properly engage the hand wheels of many different types of machines, and, as before stated, practically all machines are provided with a bearing boss on which the frame member 24 may be detachably secured, the fixed bearing points 29 in combination with the adjustable bearing point 31 providing for the clamping of the supporting frame very effectively on bosses or sleeves of various diameters, the cradle member being freely pivoted to the supporting frame, so as to swing up and down on the guide rod 33. 110 The pulley 27 rests by gravity against the periphery of the machine wheel at the rear of the latter, as shown in Fig. 4, the weight of the motor being exerted in a downward and forward direction as it is held some- 115 120 125 130

what to the rear of the position in which it would normally hang from the rod 33, by engagement with the machine wheel. In order to prevent the pulley from pressing too hard on the machine wheel, the screw 40 is used. By depressing the arm 39 of the cam member, the cam 37 presses on the cradle member in such a manner as to lift the motor from the machine wheel, as will be obvious. When the motor is in just the proper position to produce the desired amount of friction between the pulley and the machine wheel, the set screw 40 is tightened, so as to clamp the cam member in a fixed position on the rod 33, and therefore the cradle member and motor are clamped in the desired position. The cam member with its arm 39 forms a very effective means for raising the motor out of engagement with the machine wheel, and if desired the motor may be clamped by the set screw 40 in a completely disengaged position. The main value of the set screw 40 is that it permits the machine wheel to be relieved of a portion of the weight of the motor in a regulable manner, so that just the right amount of friction for driving the sewing machine in the most efficient manner can be obtained.

It will be understood, of course, that the swinging mounting of the motor member on the supporting frame permits the attachment to be used successfully in connection with sewing machine wheels of different diameters. When a sewing machine of larger diameter than that shown in Fig. 4 is employed, it is merely necessary to swing the motor member a little farther to the rear, whereas when the diameter of the machine wheel is less than that shown in Fig. 4, the cradle supporting the motor will hang down in a more nearly vertical position. By the construction described, it will be obvious that the motor accommodates itself automatically to the machine wheel. Preferably, the motor pulley engages the machine wheel by gravity, but modifications may be made in this regard while still retaining other features of the invention.

Preferably, the guide rod 33 is detachably secured to the frame member 24 by a screw 47 threaded through the wall of the socket in the extension 32, in which the rod 33 is inserted. This enables the attachment to be conveniently shipped in knock-down condition. It will be observed that the rod on which the motor member is suspended is located preferably at the rear of the usual spool-supporting pin 48 of the sewing machine shaft, and the motor member is mounted to swing in a plane parallel to that of the machine wheel in an upward and downward direction about an axis located somewhat eccentrically with respect to the machine wheel axis and disposed to one side of such axis, preferably at the rear side thereof, as described. It will be obvious from the foregoing that the parts of the improved attachment can be very readily packed in knock-down condition, 70 assembled, and applied to the sewing machine. When the sewing machine is not in use, the attachment can be removed very readily and the motor member 26 can be used for various other purposes. 75

In the modification shown in Fig. 9, the supporting frame consists of a flat plate 49 set on top of the machine head and having a spring fork 50 straddling and frictionally engaging the bearing boss 23 of the machine. The frame 49 is also detachably secured in place by providing a slot 51 therein, having notches 52 along one side, one of which notches is adapted to engage the spool-supporting pin 48 of the machine. 80 Along the rear edge of the supporting frame plate is a guide rod 53, on which a cradle member 54 is slidably mounted. In this case the cradle member or arm has an integral manipulating extension 55 at the upper end thereof, whereby it may be rocked about the rod 53 as a pivot and no means for fixing the cradle arm in place on the guide rod is provided, although such means might be provided if desired. 85

In referring in the claims to a gravity acting motor and the engagement of the drive pulley with the machine wheel by gravity, I do not, of course, wish to be understood as excluding the use of means for preventing the weight of the motor from acting on the hand wheel to a greater or less extent, as herein indicated; on the other hand, I simply intend to indicate by this broad language that the drive pulley on the 90 motor shaft has a tendency to engage or to lie in close proximity to the machine wheel. 95

It will be obvious that other modifications of the improved motor attachment will suggest themselves to those skilled in the art, 100 without departing from the principles of my invention. 110

What I claim is:

1. The combination with a sewing machine having a head and a wheel, of a motor mounted on the head in driving engagement with the wheel, adjustable longitudinally of the head through a considerable distance and urged by gravity into driving engagement with the wheel. 115
2. The combination with a sewing machine head having a shaft and a wheel at one end of the head, of a gravity-acting motor member detachably applied to the machine head for driving said wheel, said motor member being adjustable about an axis parallel to the axis of the wheel, and means for securing it in adjusted positions. 123
3. The combination with a sewing machine head having a shaft, and a driving wheel on 130

the shaft, of a frame secured to the head and extending longitudinally thereof on the headward side of the wheel and above the horizontal plane of the wheel axes, and a motor supported upon the frame for longitudinal adjustment along the machine head to various operative positions.

4. The combination with a sewing machine head having a shaft, and a driving wheel on the shaft, of a frame secured to the head and extending longitudinally thereof on the headward side of the wheel, and a motor supported upon the frame for longitudinal adjustment along the machine head to various operative positions, and urged by gravity into driving relation with the driving wheel.

5. The combination with a sewing machine head having a shaft at one end, and a wheel on said shaft, of a motor member for driving said wheel frictionally, a supporting member for said motor member secured thereto, and means for attaching said supporting member to the head so that the motor member is disposed at one side of the head and on the headward side of the wheel, said motor member being slidable on its support toward and away from the wheel, and means for securing said motor member in the desired adjustment.

6. The combination with a sewing machine having a shaft at one end and a wheel on said shaft, of a motor member having a pulley for driving said wheel frictionally, a supporting member for said motor member secured to and located beneath the latter, and extending upwardly along the body thereof, and means for mounting the upper portion of said supporting member on the sewing machine head so that said motor member can swing in a vertical plane, substantially parallel to the plane of the wheel.

7. The combination with a sewing machine head having a shaft at one end and wheel on said shaft, of a motor member having a drive pulley for driving said wheel frictionally, a supporting arm secured beneath said motor member and extending upwardly along the body thereof, and means for mounting the upper portion of said supporting arm on the machine head so that it can swing in a substantially vertical plane, parallel to the plane of the wheel to bring the driving pulley into and out of engagement with the machine wheel.

8. The combination with a sewing machine having a head with a shaft at one end and a wheel on said shaft, of a motor member having a pulley for driving said wheel frictionally, said motor member located at the headward side of the wheel, a frame member secured to the machine head, and a depending supporting arm for said motor member swingingly mounted on said frame member on a substantially horizontal axis

to provide for the movement of the drive pulley into and out of engagement with the machine wheel.

9. The combination with a sewing machine head having a wheel at one end, of a motor member for driving said wheel frictionally, located on the headward side of the wheel, a depending supporting arm beneath said motor member, and means for mounting said supporting arm from the head so that it can swing in a plane perpendicular to the wheel axis, whereby it is maintained by gravity in driving relation with the machine wheel.

10. The combination with a sewing machine having a head and a wheel, of a motor mounted on the head in driving engagement with the wheel and adjustable longitudinally of the machine head, and means for fixing the motor in the desired longitudinal adjustment.

11. The combination with a sewing machine head having a wheel at one end, of a motor member for driving said wheel frictionally, located on the headward side of the wheel and swingingly mounted from the machine head to engage and disengage the wheel, said motor member also being adjustable longitudinally of the head toward and away from the machine wheel through a considerable distance, and means for fixing the motor member in the desired adjustment.

12. The combination with a sewing machine having a head and a wheel at one end of the head, of a motor member having a drive pulley for frictionally engaging said machine wheel, the body of said motor member being located at the headward side of the wheel, and means for supporting the motor member from the upper part of the sewing machine head so that said motor member can be adjusted longitudinally of the head to various operative positions.

13. The combination with a sewing machine having a head and a wheel at one end of the head, of a motor member having a drive pulley for frictionally engaging said machine wheel, and means to support said motor comprising a supporting member mounted at the upper part of the head and depending downwardly therefrom and having its lower end secured to the motor member, the body of said motor member being located at the headward side of the wheel, and being adjustable longitudinally of the head to various operative positions.

14. The combination with a sewing machine having a hand wheel, a shaft therefor and a bearing around said shaft, of a motor attachment secured to said bearing and arranged to drive said wheel frictionally.

15. The combination with a sewing machine having a frame, a shaft journaled therein, a bearing sleeve around the shaft, and a wheel on said shaft, of a supporting frame detachably secured to the machine

frame above said bearing sleeve, and a driving motor for said wheel carried by said supporting frame.

16. The combination with a machine head 5 having a wheel, of a motor member having a pulley for driving said wheel frictionally, the axes of said pulley and wheel being substantially parallel in operative position, a supporting member located beneath and detachably secured to the under portion of said motor member, and means for mounting said supporting member to swing in a substantially vertical plane so as to move the drive pulley toward and from engagement with 15 the machine wheel, while maintaining the parallelism of said axes, said means including a supported member attached to the upper part of the machine head and depending downwardly therefrom.
20. 17. The combination with a sewing machine having a wheel, and a shaft bearing, of a drive motor for the wheel having a mounting extending around the shaft bearing, and means for clamping said mounting 25 detachably to said bearing.

18. The combination with a sewing machine having a wheel, and a machine frame provided with a laterally projecting bearing boss adjacent said wheel, of a motor attachment 30 mounted supported from said bearing boss.

19. The combination with a sewing machine having a wheel, and a laterally projecting bearing boss on the machine frame adjacent said wheel, of a motor attachment 35 detachably secured to said bearing boss.

20. The combination with a sewing machine having a wheel and a bearing boss adjacent said wheel, of a motor member for driving the wheel, swinging supporting 40 means for said motor member, and means for securing said supporting means to said bearing boss.

21. The combination with a sewing machine having a wheel and bearing boss adjacent 45 said wheel, of a gravity acting motor attachment for driving said wheel having a supporting member detachably secured to said bearing boss.

22. The combination with a sewing machine having a wheel, and a bearing boss adjacent said wheel, of a supporting frame secured to the bearing boss, and a motor member 50 swingingly mounted on said frame and adapted to drive said wheel, said motor member being adjustable longitudinally of the wheel axis.

23. A sewing machine head having a bearing boss and a driving attachment comprising a member adapted to detachably engage 55 the bearing boss and an electric motor carried by said member.

24. The combination with a sewing machine having a head with a wheel at one end, of a motor member having a casing located at the headward side of the wheel and provided with a pulley for driving the machine wheel frictionally, means for detachably supporting the motor member from the sewing machine head so that said motor member can swing in a vertical plane to engage 70 the drive pulley with and disengage it from the machine wheel, means for varying the frictional engagement between said drive pulley and said machine wheel, said motor member being adjustable longitudinally of 75 the head toward and away from the machine wheel, and means for fixing the motor member in the desired adjustment.

25. A sewing machine driving attachment, comprising a supporting frame, means for 80 securing the same detachably to the machine head, an arm pivotally and dependingly mounted on said frame to swing up and down, a motor on said arm having a drive pulley for engaging the machine wheel frictionally, and means for securing the motor 85 detachably to said arm.

26. A sewing machine driving attachment comprising a frame member adapted to detachably engage the bearing boss of the machine, and a motor member detachably connected with said frame member.

27. A sewing machine driving attachment comprising a frame member with a crescent-shaped portion adapted to be detachably 95 clamped on the bearing boss of the machine.

28. A sewing machine driving attachment comprising a frame member with a crescent-shaped portion adapted to be detachably 100 clamped on the bearing boss of the machine, and a motor member supported by said frame member.

29. In combination, a sewing machine head, a motor, and means for supporting the motor from the head comprising a supporting member mounted adjacent the upper portion of the head and depending downwardly therefrom, and having its lower end secured to the lower portion of the motor body.

30. The combination with a sewing machine head of a motor supporting member mounted thereon, at the upper part thereof, for pivotal movement and also for movement of translation for a considerable distance, said member depending from its point of support and having its lower end secured to the motor.

In witness whereof, I have hereunto set my hand on the 18th day of December, 1917.

OSCAR P. ERHARDT.
